UNITED STATES PATENT OFFICE.

WILLIAM F. CLERK, OF BOSTON, MASSACHUSETTS.

FIRE-ESCAPE.

SPECIFICATION forming part of Letters Patent No. 276,669, dated May 1, 1883.

Application filed March 5, 1883. (No model.)

To all whom it may concern:

Be it known that I, WILLIAM FARQUHARSON CLERK, of Boston, in the county of Suffolk, of the Commonwealth of Massachusetts, have invented a new and useful Improvement in Fire-Escapes; and I do hereby declare the same to be described in the following specification, and represented in the accompanying drawings, of which—

10 Figure 1 is a side view of a fire-escape of my improved kind. Fig. 2 is a side view, and Fig. 3 a longitudinal section, of the tubular or compressible shield of such fire-escape, the said Figs. 2 and 3 being on an enlarged scale.

15 My invention relates to that class of fire-escapes by which the descent of a person from a building or fire is effected by means of a rope depending therefrom, such invention consisting mainly in the means by which, while descending the rope, the person is supported and able to regulate the velocity of his descent, and his hands are protected from abrasion or injury through contact with the building, the 20 nature of my said invention being defined in 25 the claims hereinafter presented.

In the drawings, A denotes the rope, which at one end may be furnished with a hook, a, or some other suitable means of attaching it to a building or to some object therein. The 30 rope extends through a tubular slider, B, formed mainly of a short piece of hose of india-rubber or strong leather, or other suitable and easily-collapsible material. At its upper end the tube has fixed within it a metallic or other 35 proper bushing, b, while at its other or lower end it has fixed in it another such bushing, c, provided with a circular projection or hand-guard, d, and a tubular knob, e, arranged and formed as represented. The hand-guard is for 40 two purposes, viz: to prevent the hands of a person, when grasping the slider, from slipping off it or from being drawn into contact with the front or face of a building and injured or abraded thereby while he may be descending 45 the rope in order to escape from the building. Furthermore, the knob is to enable a rope pro-

vided at its lower part with a loop or stirrup to be tied or fastened at its upper part to the slider. In Fig. 1 the rope having the loop or stirrup to receive the foot or feet of a person 50 is shown at d'.

In using the slider it, having the rope A extending through it lengthwise and depending from a building, is to be seized or grasped by the person by both his hands and firmly compressed upon the rope. Having swung himself downward he, by compressing the slider on the rope more or less, as may be required, can regulate by the friction produced his rate 55 of descent, the guard keeping his hands in the meantime out of contact with the building. Prior to making the descent or after he may have commenced it, he can place one or both of his feet in the stirrup, and thus save himself the necessity of hanging by his arms, in 60 which case his hands will be free to compress to the best advantage the slider on the rope.

I claim in the fire-escape as described—

1. The flexible or elastic tubular slider provided with the annular guard, arranged with 70 it, as and for the purpose as set forth.

2. The flexible or elastic tubular slider provided with a circular guard and the tubular knob, arranged and adapted substantially as 75 represented.

3. The compressible slider provided with the guard and the stirrup or looped rope, and adapted to a rope in manner and to operate therewith, substantially as and for the purpose as hereinbefore explained.

4. The compressible slider consisting of the collapsible tube, its tubular bushings and circular guard arranged as set forth.

5. The compressible slider, consisting of the collapsible tube, its tubular bushings, circular 85 guard, and the knob or stirrup attachment, substantially as set forth.

WILLIAM FARQUHARSON CLERK.
